UNITED STATES PATENT OFFICE.

PAUL F. WACHENHUSEN, OF BRIGHTON, AND FREDERICK H. WACHENHUSEN, OF MALDEN, MASSACHUSETTS.

PAY ENVELOPE.

Application filed June 2, 1921. Serial No. 474,445.

To all whom it may concern:

Be it known that we, PAUL F. WACHENHUSEN and FREDERICK H. WACHENHUSEN, citizens of the United States, respectively, 5 the former a resident of Brighton, Boston, county of Suffolk, Commonwealth of Massachusetts, the latter a resident of Malden, County of Middlesex, in said Commonwealth of Massachusetts, have invented an 10 Improvement in Pay Envelopes, of which the following description, in connection with the accompanying drawings, is a specification, like characters on the drawings representing like parts.

15 This invention relates to envelopes and particularly to pay envelopes so called, and its object is to provide a novel envelope for that purpose having, among others, the advantages herein pointed out.

20 In the drawings of one embodiment of my invention illustrated and described herein,

Fig. 1 is a plan of the envelope closed;

Fig. 2, a similar view of the envelope open, and on a larger scale; and

25 Fig. 3, a similar view of a slightly modified form of the envelope.

Referring to Figs. 1 and 2, my novel envelope comprises a back member 1, near one end of which there is attached thereto a 30 pocket forming flap or member 2, forming the pocket 3. This member in the present case comprises the inturned flange portions 4 of the back 1 connected by a member 5 under-lapping the edges thereof.

35 This pocket is designed to receive the pay of the employee. The back 1, Fig. 1, is creased for folding along lines 6, 7, thus forming two flaps 8, 9, the former overlying and enclosing completely the pocket 2, while 40 the latter and narrower flap 9, is adapted to be folded again and secured to the opposite face of the back 1, by means of the adhesive 10 on the edge of the flap in the usual manner.

45 On the inner face of the flap 8 we provide a table or arrangement of columns and lines for the convenience of the employee, and by means of which he can keep an account of his time on which the amount of his pay in 50 the envelope is computed.

In the column 11 appear the days of the week and in the column 12 may be set down the number of hours he works each day. In column 13 is provision for any fines with 55 which he is to be charged, as for being late,

and in column 14 he may keep a record of the number of hours he works overtime and for which he is entitled to extra pay.

Furthermore, the pay envelope serves the purpose of a pocket book in which the party 60 may keep his money, as well as a memorandum book.

The space on flap 8, Fig. 2, also offers valuable opportunity for advertising matter 65 15, because each time the owner opens his envelope he must see the reading matter directly opposite the same. Also similar matter may be placed upon the pocket flap 5 for the same reason. It will be noted that the back is adapted to be severed along 70 the dotted line 7-7 to open the envelope and thus provide an ungummed flap for the structure when used as a pocketbook.

In Fig. 3, a modified form of the record is 75 illustrated and in which several sheets 16 are stitched or otherwise fastened to the back 1, each of which may contain reading matter and a series of lines under the heading for each day of the week for making a number of entries of hours, fines, etc. This 80 form of tabulation is particularly adapted for parties who perform various duties during the day and desire to keep a separate account of time consumed by each duty.

On the sheet 16 may be printed a scale of 85 charges for certain services or instructions, or working rules and regulations.

Claims.

1. A combined pay envelope and pocket-book comprising a back member with a 89 pocket on the inner face thereof, record recording spaces also on said face, the back adapted to be folded between the pocket and record spaces to constitute (part of the back) a flap for the envelope and pocket-book, the back scored near one end and also gummed at such end to provide an adhesive flap adapted to be folded against the outside of the back and opposite the pocket when the structure is used as an envelope, 95 the back adapted to be severed along the scored line to open the envelope and thus provide an ungummed flap for the structure when used as a pocketbook with record therein of the data on which the pay was 100 computed.

2. A combined pay envelope and pocket-book comprising a back member with a pocket on the inner face thereof occupying substantially one half only of the area of 110

said back member, the back being length-wise scored and adapted to be folded at the mouth of said pocket, said back member having a sealing flap at its edge most remote from said pocket, the back being scored near the flap so that the flap may readily overlie the back of said pocket and be secured adhesively thereto when the structure is adapted to be used as an envelope, the structure being adapted to be severed along the scoring line at the edge of the flap to open the envelope and thereby provide an

ungummed flap for the structure when used as a pocket book, the portion of the back member not occupied by the pocket constituting an overlying part for the pay envelope when used as such and also constituting one of the swinging members of the pocketbook when the structure is used as such. 15 20

In testimony whereof, we have signed our names to this specification.

PAUL F. WACHENHUSEN.

FREDERICK H. WACHENHUSEN.
